UNITED STATES PATENT OFFICE.

GUSTAVE M. FAUSER, OF ARDSLEY-ON-HUDSON, NEW YORK, ASSIGNOR TO PENNSYLVANIA TEXTILE MILLS, INC., OF CLIFTON, NEW JERSEY, A CORPORATION OF NEW JERSEY.

DESIGN FOR A TEXTILE FABRIC.

Application filed March 2, 1926. Serial No. 16,742. Term of patent $3\frac{1}{2}$ years.

To all whom it may concern:

Be it known that I, GUSTAVE M. FAUSER, a citizen of the United States, residing at Ardsley-on-Hudson, in the county of Westchester, State of New York, have invented a new, original, and ornamental Design for a Textile Fabric, of which the following is a specification, reference being had to the accompanying drawing, forming part thereof.

The figure is a plan view of a textile fabric showing my new design.

I claim:

The ornamental design for a textile fabric substantially as shown.

GUSTAVE M. FAUSER.
